UNITED STATES PATENT OFFICE.

FRANK OVERHOLT, OF HARLAN, IOWA.

EXTENSION-CHANDELIER.

SPECIFICATION forming part of Letters Patent No. 481,814, dated August 30, 1892.

Application filed May 31, 1892. Serial No. 434,986. (No model.)

To all whom it may concern:

Be it known that I, FRANK OVERHOLT, a citizen of the United States, residing at Harlan, in the county of Shelby and State of Iowa, 5 have invented certain new and useful Improvements in Extension-Chandeliers, as set forth in the accompanying drawings, forming part of this specification, in which—

Figure 1 represents a vertical sectional view 10 showing the telescopic tubes of an extension-chandelier and interior spirally-twisted conducting-wires and showing the parts extended. Fig. 2 is a similar view showing the tubes telescoped one within the other and the 15 conducting-wires contracted. Fig. 3 is a modification to be referred to.

My invention relates to extension-chandeliers especially adapted for electric-lighting purposes; and my invention consists of the 20 construction and combination of devices, which I shall hereinafter fully describe and claim.

To enable others skilled in the art to which my invention appertains to make and use the 25 same, I will now describe its construction and indicate the manner in which the same is carried out.

In the drawings, A, A', and A² represent a series of tubes having different diameters, 30 whereby they may slide one within the other. In the present case I have shown three tubes, and in which the upper one A is the largest and has its lower end formed with an inwardly-turned flange or screw-cap a, and its upper 35 end provided with a plate or other means for suspending the tubes from a fixed support. The middle tube A' is fitted within the upper tube and has its upper end formed with an outwardly-turned flange or screw-cap b closely 40 fitting the inner walls of the upper tube, while at the lower end of this middle tube is an inwardly-turned flange or screw-cap c. The lower tube A² is fitted within the middle tube A' and has its upper end formed with an outwardly-turned flange or screw-cap d and its 45 lower end formed or attached to any desired form of lamp socket or support B, which furnishes a support for one or more lamps or burners. (Not shown.)

50 In the lower or upper portions of the tubes A and A' spring-plates e are secured at one end and have their upper ends free and adapted to

bear inwardly against the outer walls of the middle and lower tubes, respectively, whereby the frictional contact of these spring-plates 55 will assist in holding the tubes in any adjusted position and to retain them in a closed or telescoped condition when desired. These plates also assist in steadyng the tubes when the latter are extended and prevent their being extended too far. To assist this holding of the tubes and to provide a simple means for conducting the current of electricity from its source of supply to the lamp or burner, I arrange within the central passage of the tube 65 G and H, one of which connects with the positive and the other with the negative poles of the battery in any well-known manner. These wires G and H are preferably of spring metal, 70 and being spirally coiled assist the spring-plates in holding the tubes closed, or in their adjusted positions, their coils being distended when the tubes are pulled out, as shown in Fig. 1, and contracted when the tubes are 75 pushed into each other or telescoped, as shown in Fig. 2. The wires are properly insulated from each other and the tubes, and they not only serve to carry the current, but also employ the expansive and contractive force of 80 the coils to assist in suspending the tubes when the latter are extended, and also to maintain them closed when the tubes are pushed together.

Having thus described my invention, what 85 I claim as new, and desire to secure by Letters Patent, is—

1. In an extension-chandelier, the telescopic tubes, the lower one of which is provided with means for supporting a lamp or burner, 90 said tubes having limiting-stops at their ends and one of said tubes carrying a lamp-socket, in combination with spirally-coiled wires within the tubes to be connected with the opposite poles of an electric circuit and to assist in supporting the weight of the tubes and maintain them in their adjusted positions, 95 substantially as herein described.

2. In an extension-chandelier, the telescopic tubes having inwardly and outwardly turned 100 flanges at their ends and a lamp-socket carried by the lower tube, in combination with conducting-wires within the tubes and to be connected with a source of electric supply,

said wires being spirally coiled, whereby they are distended when the tubes are extended and contracted when the tubes are telescoped, substantially as herein described.

5. 3. In an extension-chandelier having telescopic tubes with inwardly and outwardly turned end flanges, the spring-plates secured to the inner walls of the tubes, with their free ends bearing against the outer walls of adja-

cent tubes, and spirally-coiled wires extending through said tubes to assist the spring-plates in maintaining the tubes in their adjusted positions, substantially as herein described.

FRANK OVERHOLT.
